P. GROEBER.

WALL PAPER.

No. 15,241.

Patented Aug. 12, 1884.

UNITED STATES PATENT OFFICE.

PAUL GROEBER, OF NEW YORK, N. Y.

DESIGN FOR WALL-PAPER.

SPECIFICATION forming part of Design No. 15,241, dated August 12, 1884.

Application filed April 11, 1884. Term of patent 3½ years.

To all whom it may concern:

Be it known that I, PAUL GROEBER, a citizen of the United States, residing in the city of New York, county and State of New York, 5 have invented and produced a new and original Design for Wall or Ceiling Covering, but which is especially intended as a wall covering or hanging.

The drawing represents a front plan view of 10 the design.

The design is floral in its character, treated in the Venetian style of the last century. It represents open and budding flowers *a*, with palmatisected leaves and stems arranged in 15 scroll like forms *b*. In two instances, *c c*, the usual position of the mid-rib is occupied by a series of flower-buds. The interstices of the

pattern are filled in with perpendicular fine-line shading *d*.

The treatment of the subject is purely conventional, and one peculiarity of the design is that the outline of neither the stems, flowers, nor leaves is continuous, but detached, forming breaks and interruptions, even isolating portions of the design. 25

I claim—

The design for a wall or ceiling covering, shown in the print accompanying this description.

PAUL GROEBER.

Witnesses:

PHILLIPS ABBOTT,
JOHN MICHELS.
